RECORD CHANGING MECHANISM FOR PHONOGRAHS

Application filed April 16, 1928. Serial No. 270,363.

This invention relates to record changing mechanism for phonographs, particularly to a record changing mechanism for phonographs using disk records which are played on a horizontally revolving turn table; the principal object of the invention being to provide a mechanism that is entirely automatic in its operation, which makes the record changes quickly and quietly, which is of simplified construction, relatively inexpensive, and which will accommodate a various number of records.

It is also an object of the invention to provide a mechanism of the above character which will operate to transfer the record disks, one at a time, from one side of a supply group to the turn table for playing and then to replace each record on the other side of the group after it has been played. Also, in replacing the records, to invert them so that when again delivered to the turn table, the other side will be played.

Another object of the invention is to provide means for selectively controlling the number of records to be played, that is, a mechanism which may be set so as to play one side of all records in a supply stack or both sides of all records, or to cause one record to be played repeatedly.

More specifically stated, the invention resides in the provision of a record changing mechanism for phonographs using double faced disk records, and it comprises a tiltably mounted supporting rack or magazine on which a supply of records may be grouped, a transfer ring or carrier which encircles the turn table and which may be swung upwardly by the setting of a clutch incident to completion of a record, to transfer the record to one side of the supply group and, on its return movement, to receive a record from the other side of the group and to transfer this to the turn table for playing.

Other objects of the invention reside in the various details of construction and mode of operation of the mechanisms for actuating the carrier, for releasing the records from the supply group for delivery onto the carrier, for controlling the movement and setting of the reproducer, or pickup instrument,

so that it will not interfere with the removal from or replacement of a record on the turn table and will set the reproducer needle accurately in the groove of the record to be played.

Another important object of the invention resides in the provision of a circuit closing switch of novel construction, operating in conjunction with the reproducer and which operates incident to the completion of a record to close a circuit to set a clutch whereby the mechanisms which effect the record change are set in motion.

Other objects of the invention reside in the details of construction and in the combination of parts, as will hereinafter be described in detail and specifically recited in the claims terminating the specification.

In accomplishing these objects I have provided the improved details of construction, the preferred forms of which are illustrated in the accompanying drawings, wherein—

Figure 1 is a perspective view of a record changing mechanism embodied by the present invention, showing the parts in the position they assume during the playing of a record.

Figure 2 is a view illustrating the action and relation of the parts during a record changing operation.

Figure 3 is a section taken through the record supporting rack and carrier during a record changing operation and showing the parts just as a record is being replaced in the rack.

Figure 4 is a similar view, illustrating the transfer of a record from the rack onto the carrier as the latter swings downwardly and the rack swings back toward horizontal position.

Figure 5 is a side elevation from the side opposite that of Figures 1 and 2.

Figure 6 is a front view of the reproducing instrument, showing the switch used in connection therewith for closing the circuit to the clutch actuating solenoid.

Figure 7 is a detail view, illustrating the cam and its connection with the shaft which controls movement of the record supporting rack.

Figure 8 is a perspective view of the

mechanism during a record changing operation.

Figure 9 is a detail, perspective view, showing the trip mechanism whereby the records are released from the rack onto the carrier.

Figure 10 is a perspective view of parts of the setting mechanism whereby the number of records to be played is controlled.

10 Figure 11 is a plan view of the various control and driving mechanisms and a grammatic view of the circuit connections.

Figure 12 is a detail view illustrating action of the clutch setting lever under the 15 influence of the energized solenoid.

Figure 13 is a detail view, showing the releasable connection whereby repeating of a record is controlled.

20 Figure 14 is a perspective view of the tone arm raising, swinging and setting devices.

Figure 15 is a detail view of means whereby the rack and setting devices may be adjusted to accommodate the machine for records of various diameters.

25 Figure 16 is briefly described, the mechanism comprises a rack on which a supply of records to be played may be placed and a carrier whereby a record, after being played, may be transferred from the turn table to the

30 rack and which also serves, on a return movement, to transfer a record from the rack onto the turn table. The action of the transfer mechanism is started by the closing of a circuit through a solenoid which operates to set a clutch to connect the mechanism

35 with a continuously driven shaft. A switch of novel construction is provided in connection with the tone arm and this operates automatically on completion of a record to close the circuit through the solenoid and the action of the latter is to shift the clutch and to set certain parts in motion whereby

40 the tone arm is raised off of the record and swung to one side just prior to the starting action of the transfer mechanism which

45 lifts the record from the turn table and places it on the rack. A trip mechanism operates automatically to release a single record from the rack and place it on the

50 carrier as the latter returns to position about the turn table. Then, with the record in place for playing, the tone arm is brought back and accurately set on the record in playing position.

55 Referring more in detail to the drawings—

1 designates what may be termed the base board on which the various mechanisms, including the usual electric motor for operating the phonograph, are mounted and 2 is 60 the turn table supported horizontally just above the base board on a shaft 3 by means of which it is rotated by connection with the electric motor, which is represented in Figure 5 by the circular housing 4 and in Figure 11 by the broken line circle; it being un-

derstood that any suitable type of motor may be used for this purpose and connected with the turn table in any suitable manner. Adjacent the turn table is the tone arm 5 which is adapted to oscillate in a horizontal plane and also to be adjusted vertically through its guide bearings 6 in the base in the usual manner, so as to permit the needle 7 that projects downwardly from the reproducing unit or electrical pickup, designated at 8, and which is carried at the swinging end of the arm, to follow in the groove of the record, also, to permit the needle to be raised clear of the record when the arm is swung to the side of the turn table for changing a record. Electric circuit for the motor is brought thereto through circuit wires 9 and 10, as shown in Figure 11, and the circuit is under the control of a suitable switch as designated at 12.

At one side of the turn table is a rack on which the group of records to be played is supported. This rack comprises two spaced posts 13—13 that are fixed vertically in the base 1 and which, at their upper ends, pivotally support a tiltable frame; the said frame comprising parallel, opposite side bars 14—14 which extend through the blocks 15 pivotally connected, as at 16, to the posts, with the rear ends of the bars connected by a cross member 14a and their forward ends connected by a flat bar or plate 17. In this construction, the cross bar 14a and the plate 17 serve as the supports for the record stack which, as shown best in Figures 1 and 8, barely overlaps these parts, and two spaced studs, or stops, 18 are fixed in the plate 17 against which the forward edge of the stack is abutted to hold the record disks in alignment and also to support the stack when the frame is tilted vertically during a record changing operation, as will presently be described.

Except during the record changing operation, the group of records is supported by the rack frame substantially in a horizontal position, as shown in Figures 1 and 8; the rack being moved to this position and held thereby by means of an arm 20, see Figure 5, which is fixed to the rack pivot 16 at one side and which extends alongside the adjacent frame bar 14. This arm, in turn, is supported by engagement therewith of the upper end of a lever 21 that is fixed to one end of a cross shaft 22 mounted rotatably in supporting bearings 23 formed on a bar 24 which, as shown in Figure 2, is fixed to the base 1 parallel with the line of posts 13. The center of the record stack is set slightly forward of the line of the pivot points so that it will of its own weight cause the rack to tilt forwardly when the arm 20 is released. Mounted beneath the base 1 and parallel with shaft 22 in bearings 25, as shown in Figure 5, is a shaft 26, and fixed, respectively, on the shafts 22 and 26, are wheels 27 and 28 about which

a belt, or strap, 29 is extended; the belt being fixed to the wheels so as to prevent any possible slippage and the wheel 27 being somewhat smaller than wheel 25 so that a certain rotative movement of shaft 26 will cause a greater movement of shaft 22.

The downward tilting of the record supporting rack, which is necessary for each record transfer operation, is effected by swinging the arm 21 rearwardly and the return of the rack to horizontal position is effected by the return of the arm to initial position. For this purpose the shaft 26 has a crank arm 30 fixed to one end thereof and this is connected by a link 31 to a slide 32 that is actuated by a cam 33 on a horizontal shaft 34 mounted revolvably in a frame structure 35 that is suspended below the base 1 by brackets 36, as shown in Figure 5. The shaft 34 is stationary during the playing of a record, but is set in motion for the record changing operation by the setting of a friction clutch mechanism 37 which provides a driving connection between the shaft 34 and a shaft 34a aligned therewith that is continuously driven through a gearing connection, designated at 38 in Figure 11, from the lower end of the motor driven shaft 3. When the clutch is set, the shaft 34 will be revolved and the cam 33, through its connection with the slide 32 and link 31, effects an oscillating motion of the lever arm 30 and this is transferred to the shaft 26 which, through the connection of the belt 29 with the wheel 27, effects the rearward and forward swinging movement of the arm 21 which controls the movement of the stack supporting rack.

Associated with the turn table, is a carrier whereby the record disks are transferred between the table and supply stack. This carrier comprises a ring-like member 40 that is entirely independent of the table but which is adapted to encircle it, as shown in Figure 1. It is provided with an inturned flange 40a against which the periphery of the record disk may seat when carried within the ring during a transfer operation. The ring is fixed rigidly by two connecting brackets 41-41 to the shaft 22, so that the same rotative movement of the latter, which is produced to cause the record supporting rack to swing downwardly, will cause upward swinging of the ring to transfer a record from the table to the rack. It is to be understood, of course, that the record when disposed on the turn table projects beyond the periphery of the latter and that the carrier is of such diameter as to receive the record disk within it. The rack and carrier also are so arranged in this construction and their movements are so synchronized that when the carrier swings upwardly and reaches its limit of travel in this direction, the record carried therein will coincide with the records on the rack and will be discharged onto the rack and

supported there by engagement of its lower edge with the studs 18 that extend from the plate 17.

Since it is required that the tone arm 5 be raised and swung to one side of the turn table during a record changing operation, this movement is accomplished as follows: The tone arm has its mounting portion slideable in the bearing 6 and has fixed therein a downwardly extending post 45 which, at its lower end, is tapered to a rounded point 46 adapted to ride on the periphery of a circular cam 47 that is fixed to the shaft 34. At one point in the cam is an inwardly cut notch 48 within which the post may seat to lower the tone arm onto the record. During the playing of a record, the post is disposed in the notch of the cam, as shown in Figure 5, but on completion of a record, the cam is started to rotating and this causes the post 45 to be raised and the arm to be lifted thereby clear of the table 7, as shown in dotted lines in Figure 5. As the arm is thus lifted, it is also swung to one side of the turn table by the action of a cam 50 that, also, is fixed to the shaft 34 adjacent the cam 47 and which engages with a downwardly projecting post 51 fixed to an arm 52 that extends laterally from the post 45, as shown best in Figure 14. A yieldable spring arm 53, that is fixed to a block 54 on the underside of the base 1, engages with the arm 52 and thus limits the outward swing of the tone arm. It serves also as a means of returning the tone arm back over the table as the cam 50 recedes. When the tone arm is brought back over the turn table, its inward swing is stopped at a certain point so that when again lowered, the needle 7 will be positioned properly within the starting groove adjacent the outer edge of the record. This stopping of the arm is effected by engagement of the outer end of the arm 52 with a downwardly projecting stop 60 that is fixed in the block 54 and which is of such length that after the tone arm has been lowered for playing, the arm 52 may pass beneath the stop as it swings inwardly in accordance with travel of the needle inwardly toward the center of the record. When the tone arm is lifted on completion of a record, the laterally extending arm 52 is disposed within the stop post 60 and it is essential that the stop be so constructed as to permit the arm 52 to pass by it when the tone arm is swung outwardly. To permit this, I have provided the lower end of the stop post with a hingedly attached extension member 60a. This extension is so hinged that it will swing outwardly to permit arm 52 to pass outwardly but will not swing inwardly beyond the straight line of the post.

The clutch 37, as shown in Figure 11, comprises two cooperating friction disks 37a and 37b that are fixed, respectively, to the shafts 34 and 34a and which are normally held dis-

engaged by pressure of a small coiled spring 39 that is placed between them, but which will be engaged to effect a driving connection between the shafts by the inward swinging of a lever 62 that is hingedly attached at one end, as at 63, to the end of the frame 35 and which has a pivot 64 bearing against the outer end of the shaft 34. The inward swinging of this lever, from the position shown in Figure 11 to that shown in Figure 12, causes the shaft 34 to be shifted inwardly so as to press the clutch disks together and to thus cause the shaft 34 to be driven. This movement of the clutch lever is effected through a spring connection 65 with the core bar 66 of a solenoid 67 that is fixed to the frame 35. When the solenoid is energized, through connection with the main circuit, as presently described, the core is drawn inwardly and this places the spring 65 under tension and pulls the lever 62 inwardly. This action of the solenoid, whereby the clutch is set and the transfer mechanism thus set in motion, is occasioned at the completion of playing a record by the closing of a circuit through the solenoid by the automatic, momentary closing of a switch carried on the reproducer unit at the end of the tone arm. This switch, as best shown in Figure 6, comprises a stationary contact 70 mounted on a block of insulation 71 on the casing of the reproducer unit 8, with a flexible contact 72 also mounted on the block and, at one end, having a brush 73 or other device adapted to engage the face of the record disk and to follow in its grooves. The contacts 70 and 72 are normally disengaged so that the circuit to the solenoid is open, but are brought together incident to the continued inward travel of the brush toward the center of the record after the reproducing needle 7 has reached the continuous, circular groove formed in the disk at the end of the record groove; it being apparent that the needle reaches the continuous groove in advance of the brush and that, since the brush is following in the spiral grooves of the record, it will be crowded over against the contact 70.

The wiring diagram of Figure 11, whereby the circuit connections between the motor and the various switches are disclosed, shows the motor 4 to be connected with the main circuit wires 9 and 10 by means of circuit connections 76 and 77; the latter having a switch interposed therein which comprises a fixed contact plate 78 and a yieldably mounted contact plate 79, these being associated with the automatic stop mechanism which presently will be described. A circuit wire 80 connects one side of the solenoid with the circuit wire 77 between the motor and the cut-out switch and a wire 81 connects the other side of the solenoid with a binding post 82 that is mounted on, but insulated from, the lever arm 62. A wire 83 connects the bind-

ing post 82 with the contact 72 of the switch carried on the tone arm and a wire 84 connects the contact 70 with a wire 85 which connects with wire 76 and a post 86 that is mounted in the frame 35 just within the lever 62. This latter post 86 is adapted when the lever 62 is drawn inwardly by action of the solenoid to engage with a contact 88 carried by the lever 62. With the circuit connections so established, it is apparent that the bringing together of the contacts 70 and 72 on the completion of a record will close a circuit through the solenoid which will cause the core thereof to be drawn inwardly and the lever 62 to be moved accordingly to seat the clutch 37 and thus cause the shaft 34 to be driven in accordance with the continuously driven shaft 34a.

I have also provided a shunt circuit connection around the switch on the tone arm consisting of a wire 89 connecting wires 83 and 84 with a normally open push button switch, designated at 89a, interposed in the connection.

It will be stated here that since the circuit through the solenoid as controlled by the switch carried on the tone arm is only temporary, it is necessary to provide other means for keeping this circuit closed after the contacts 70 and 72 are separated. This is accomplished by the circuit connecting wire 85 which carries the circuit to the post 86 from which it passes through the contact 88 and wire 81 to the solenoid after the circuit through the wire 83 is opened.

As the shaft 34 starts to rotate incident to setting of the clutch 37, the cam 47 acting on the post 45 causes the tone arm to be lifted upwardly while the cam 50 acting against the post 51 depending from the arm 52 causes the tone arm to be swung to one side clear of the record and turn table. Rotative movement of the shaft 34 also causes the cam 33 through the link 31 and arm 30 to actuate the rock shaft 26 so as to swing the lever arm 21 rearwardly and to permit the rack on which the supply of records is supported to swing downwardly from the horizontal position of Figure 1 to the inclined position of Figure 2.

As the rack is thus being tilted downwardly, the carrier 40 swings upwardly and carries the record with it from the turn table and deposits it on the rack. While the carrier and rack are in this position, the lower record of the supply is released for disposition on the carrier when the latter swings downwardly to normal position. The means whereby the record is released, as best shown in Figures 1 and 9, comprises a trip lever 90 that lies against the outer face of the plate 17 and is pivotally connected thereto by a pin 91. The inner end of this lever is disposed against the lower edge of the lower record of the stack while its outer end projects beyond the end of the plate 17. Pivotally attached to the post

13 at that end of the rack, by means of a pivot pin 92, is a short, forwardly directed lever 93 and pivotally connected with the outer end of this lever, is a downwardly depending link 94 having a laterally turned foot 95 at its end.

5 The construction and arrangement of these parts is such that when the record supporting rack swings downwardly, the outer end of the lever 90 passes to a position beneath the outer end of the lever 93 and, when the lever arm 21 10 swings rearwardly and downwardly, it is brought into engagement with the outturned foot 95 of the link 94 and, through this link, draws the lever 93 downwardly so that its end engages with the end of the lever 90 and rocks 15 the inner end of the latter upwardly, thereby unseating the lower record of the group from the cross plate 17 and allowing the record to drop against two spaced cushioning members 98 that are fixed on the base plate 1 centrally 20 between the posts 13 and back of the shaft 22. The released record is supported on the cushioned members, as shown in dotted lines in Figure 3, by two inwardly and downwardly directed bars 99 against which the record 25 leans. These bars are fixed in blocks 100 mounted on the opposite side bars 14 of the rack frame, and they extend downwardly in converging relation. As soon as a record is 30 released, the rack and carrier start on their return movements and as the carrier swings downwardly from the position shown in Figure 3 through the position as shown in Figure 4, the rack is also moved back toward the 35 horizontal position; this movement of the rack being effected by the upwardly swinging arm 21 coming into engagement with the arm 20. As the carrier swings downwardly, a rearwardly and upwardly directed prong 105 that is fixed to its rearward edge comes into 40 contact with the lower edge of the released record and lifts it from the cushioning blocks 98 and causes it to slide into the carrier; then, as the rack swings upwardly, the record slides 45 down along the inwardly converging arms 99 and onto the turn table to the dotted line position of Figure 4. As the carrier continues to move downwardly the record is farther advanced onto the turn table by the arms 99 and 50 finally, as the carrier assumes a horizontal position, the record drops from the ends of the arms and is centered in the ring and on the turn table in position for playing.

When the rack swings downwardly to the 55 position shown in Figure 3, its movement is limited by stops 107 that are adjustably mounted by blocks 108 carried on the posts 13 and, when the record is released from the rack, it is retained against rearward slipping 60 on the cushioning blocks by a cushioning stop block 110 carried by a bracket 111 that extends upwardly beyond the top of the cushioning blocks 98. The prong 105 that is fixed to the ring 40 is then disposed between the 65 cushioning blocks 98 so that it will properly

engage the record for transferring the latter onto the ring when the latter swings downwardly.

For the purpose of resetting the lever 90, after it has unseated a record from the rack, 70 I provide a block 115 that is mounted on the arm 21 at a position at which the outer end of the lever 90 will be engaged therewith when the record supporting frame swings upwardly and by this engagement will be 75 moved back to initial position. The arrangement is best shown in Figure 9, which shows the relation of parts just after the record has been tripped. In the resetting, the lever 21 swings upwardly and forwardly as the rack 80 swings upwardly and, during this upward swinging, the outer end of the lever 90 rides over the rounded edge 115a of the block 115 to effect the resetting of the lever.

A spring wire 116 is wrapped around the 85 pivot 92 and bears against the lever 93 to urge the latter to an upwardly directed position after it is released from the arm 21, and there is also a spring wire 117 attached to the arm 21 and provided at its end with a hook 90 118 adapted to engage a pin 119 in arm 20 as a safety device to prevent the possibility of the rack tilting rearwardly when it is returned to horizontal position.

The record changing operation is all 95 accomplished during one revolution of the shaft 34 which is set in motion by the setting of clutch 37 incident to closing a circuit through the solenoid. The circuit through the solenoid is broken when the cam 47 has 100 made one complete revolution and, just as the tone arm supporting post settles into the cam notch 48 and sets the needle on the record, by the action of a cam block 47a fixed to the outer face of the cam 47, see Figure 11, 105 in a position at which it will be brought into contact with a slide pin 47b which is carried in the end bar of frame 35 and which will be moved outwardly thereby against the lever 62 to move the latter outwardly and break 110 the circuit connection between pin 86 and contact 88.

For setting the device to automatically stop itself after playing a selected number of records, I have provided a switch actuating 115 mechanism operating in connection with the shaft 26 and the cut out switch in the wire connection 77. The setting device consists of a knob 120 fixed in the upper end of a shaft 121 rotatably mounted in a bracket 122 fixed to the underside of the base 1, with the shaft extending upwardly through the base. On the lower end of the shaft is a wheel 124 having a plurality of radially extending pins 125 therein, one of which, here designated 125a, is considerably longer than the others and is adapted to be brought into contact with the yieldable contact 79 of the controlling switch. On the end of shaft 26, which overlies the wheel, is a block 126 in which a

pawl 127 is pivotally mounted for swinging movement from and against a stop shoulder 128 in its mounting block. This pawl depends between the radial pins and is so arranged that, with each rearward oscillatory action of shaft 26 incident to transfer of a record from the stack to the table, successive pins 125 will be engaged thereby and the wheel 124 rotatably advanced. Thus, each 10 operation advances the long pin 125a one interval closer to the switch and finally brings it against the contact 79, as in Figure 11, and pushes the latter from the contact 78 and opens the motor circuit to stop the machine. 15 Fixed to the base 1 about the shaft 121 and beneath the knob 120, is a plate or dial 130 that has graduations numbered in accordance with the radial pins of the wheel and a pointer 131 is fixed to the knob to follow the 20 markings and by means of which proper setting of the wheel may be made to indicate the number of records that can be played before the cut out switch will be actuated. This arrangement provides that, if there are ten records in the stack and it is desired to play all of them, the pointer is set at 10 on the dial. The relation of the pointer to the long pin is such that after ten records have been played, the next advance movement of 25 wheel 124 brings the long pin 125a against the switch contact 79 to open the circuit and stop the machine. If it is desired to play both sides of the ten records, the pointer would be set at 20 on the dial. This causes all records 30 to be played through once on one side, then once on the other. Other settings for any selected number of records may be made.

It will be noted also that at one point of the wheel 124, as shown in Figure 11, one 40 of the radial pins 125 is omitted, thus leaving an open interval. By adjusting the pointer to register with a repeat mark on the dial, this open interval will be moved to a position at which the pawl 127 will operate 45 within it and the wheel will not be advanced, thus the machine may be made to operate for any length of time without automatically stopping itself.

I have also shown in Figure 13 means for 50 releasing the wheel 28 from the shaft 26 so that motion will not be transmitted to the shaft 22 to produce the record changing operation, and thus, a selected record may be repeated as many times as desired. This 55 release consists of a flexible wire 130a that extends radially into the wheel and through a hole 131a in the shaft. It is contained within a flexible tube 132 fixed at its ends in the wheel and in the base 1, and at its outer 60 end has a button 133 fixed thereon. By drawing upwardly on the button, the wire will be withdrawn from the hole in the shaft and the latter will then operate freely in the wheel 28 and no movement will be transmitted to 65 the rack or carrier by the rotation of shaft

34, although the resetting of the tone arm will be effected in the same manner as if a new record was placed in position.

In Figure 15, I have shown a modification wherein provision is made for adjusting the parts so as to accommodate the device for playing records of different diameter; it being apparent that for this purpose it would be necessary to adjust the record supporting rack rearwardly or forwardly in accordance with the diameter of the record, and also that it would be necessary to adjust the stop post 60 to a position for properly setting the needle on the record. In the arrangement illustrated, the posts 13 are mounted on a plate 140 that is slidably mounted in supports 141 fixed to the underside of the base. Likewise, the post 60 is carried by a plate 142 slidably mounted in a guide 143 fixed to the underside of the base. A rock shaft 145 is mounted beneath the base in supports 146 and this has rocker arms 147 connected with the plates 140 and 142 by links 148 and 149, respectively. Means would be provided whereby the shaft 145 could be rotated so as to effect the simultaneous adjustment of the rack which is carried by the posts 13 and the stop post 16. With the foregoing adjustment and the substitution of a hoop 40 of greater diameter, or the use of a hoop having depressions of greater diameter to receive records of various diameters, the adjustment is complete.

Assuming the device to be so constructed, to operate the same, it is only necessary to place a supply of records on the rack when the latter is in horizontal position, as shown in Figure 1. Then, on pressing the button 89a, a circuit will be closed through the solenoid and this, as previously described, effects the setting of the clutch whereby the record transfer mechanism is set in motion. The tone arm will be first moved to the side of the turn table, the carrier will swing upwardly as the rack is tilted forwardly and downwardly and, on return movement of the rack, a record will be discharged and delivered onto the carrier for placement on the turn table in position for playing. The tone arm then automatically swings back and is set on the record at the starting point.

When the needle reaches the inner circular groove on the record, the switch contacts 70 and 72 will then be brought together to close the circuit through the solenoid automatically and effect the changing of the records. This automatic action will continue so long as is desired, or for any specified number of selections, in accordance with the setting of the knob 120 which controls the automatic stop and repeat mechanism.

If it is desired to repeat any record, this may be accomplished by setting the control device on the repeat mark and by withdrawing the wire which fixes the wheel 28 against rotation on the shaft 26; this being done by pulling upward-

ly on the button 133. Should it be desired to change a record at any time before the selection being played is completed, it is only necessary to press on the switch button 89a and this closes a circuit through the solenoid to start the record changing action.

It is readily apparent that devices of this character may be made to accommodate records of various diameter and of various thicknesses, and that the adjusting mechanism as disclosed in Figure 15, could be embodied with the machine if desired, so that required adjustments may be made simultaneously and easily by the rotation or adjustment of a single shaft.

It is readily apparent that various details of construction and combination of parts could be changed without departing from the spirit of the invention and, for this reason, it is not desired that the claims be limited only to the details as herein illustrated. It is also apparent that this record changing mechanism can be used in connection with the ordinary type of phonograph wherein the tone arm 5 connects with an amplifying horn, or it can be used in connection with electrical pickups for radios wherein the tone arm serves simply as a carrier for the reproducer mechanism 8 and the needle 7.

Having thus described my invention, what I claim as new therein and desire to secure by Letters-Patent, is:

1. In a machine of the character described, a turntable, a rack adjacent thereto for supporting a group of records in contacting relation, an oscillating carrier operable between the rack and turntable, means for delivering records one at a time from one side of the group onto the carrier for placement thereby on the turntable and means operable to move the carrier to return the records to the other side of the group and to invert them during the return movement.

2. In a machine of the character described, a turntable, a rack for supporting a supply of records adjacent thereto, a carrier whereby records may be returned from the turntable to the rack in an inverted position, a trip device operable incident to the return of a record to the rack, to release another record therefrom, guide members extended from the rack and means for causing the released record to follow along the guide members to the carrier for placement thereby on the turntable.

3. In a machine of the character described, a turntable, a pivotally mounted rack on which a supply stack of records may be supported, means for tilting the rack to adjust the records from upright to a vertically inclined position, a carrier operable to return records from the turntable onto the rack when the latter is in an inclined position, a trip adapted to be actuated incident to a record return movement of the carrier to release

a record from the rack, and guides attached to the rack along which the released record will be caused to slide incident to return movement of the rack to upright position and to be positioned thereby on the carrier for placement on the turntable.

4. In a machine of the character described, a turntable, a magazine for containing a plurality of record disks disposed adjacent thereto, an oscillating carrier of fixed ring-like form upon which the records may be individually received and whereby they may be positioned concentrically on the turntable for playing and mechanism for actuating said carrier to return the played records from the turntable back to said magazine.

5. In a machine of the character described, a turntable, means for supporting a plurality of record disks adjacent thereto, and a record changing means including a carrier of ring-like form within which the records may be individually received and supported, means for swinging the carrier from a horizontal position, at which it concentrically encircles the table, upwardly through and slightly beyond vertical position for lifting a record from the table and for delivering it onto the supply of records and means operable during return movement of the carrier for transferring a record from the supply onto the carrier for placement thereby on the table.

6. In a machine of the character described, a turntable, means for supporting a supply of record disks adjacent thereto, a carrier of ring-like form, means for oscillating the carrier upwardly through and slightly beyond vertical position, for returning a record from the table to the supply of records and then back to its normal position, and means for transferring a record disk from the supply onto the carrier on its return movement to be centered thereby on the table.

7. In a machine of the character described, a turntable, a magazine for containing a supply of record disks supported adjacent thereto, a record changing means comprising a carrier adapted to be oscillated between the table and the supply of disks for transferring them individually from the magazine to the turntable and back to said magazine, a reproducing element, a swingingly mounted supporting arm for said element and means for swinging the arm away from the table for a record changing operation and for returning it to playing position after said change.

8. In a machine of the character described, a turntable, means for supporting a supply of record disks adjacent thereto, an oscillating carrier operable to transfer records from the table to the supply and from the supply onto the table, a reproducer element, a tone arm for the reproducer adapted to raise and lower the reproducer element from and into playing position and to be swung laterally for removing it therefrom for a record changing

operation, a driven shaft and mechanisms operable by the shaft for actuating the record changing means and for actuating the reproducer element supporting arm.

9. In a machine of the character described, a turntable, a supply of disk records, a record changing means whereby the disks are transferred from the table to the supply and from the supply onto the table, a reproducer element, means for adjusting the reproducer from and into playing position incident to a record changing operation, normally inactive driving means for the record changing and reproducer adjusting mechanisms, a driven member, a clutch adapted to be set to effect a driving connection between the driven member and said normally inactive driving means, an electrically operated clutch setting device, a circuit for said device, a control switch for said circuit, and means operated by a characteristic of the record being played for actuating the switch to close the circuit.

10. In a machine of the character described, a turntable, a supply of record disks, a record changing means for transferring records one at a time from the supply to the table and for returning them to the supply, a reproducer, means for adjusting the reproducer from and into playing position incident to each record change, normally inactive driving means for the record changing and reproducer adjusting means, a driven member, a clutch operable to effect a driving connection between the driven member and said normally inactive means, a solenoid, a circuit for the solenoid, a switch for controlling said circuit operable by a characteristic of the record being played to close the circuit to actuate the clutch and means operable incident to completion of a record changing operation for opening the circuit.

11. In a machine of the character described, a turntable, means for supporting a supply of record disks adjacent to the turntable, a record transferring means movable between the supply and the turntable for the transferring of records from the supply to the turntable and from the turntable to the supply, and means for adjusting the record supporting means relative to the table for the accommodation of records of different diameters.

12. In a machine of the character described, a turntable, means for supporting a supply of record disks adjacent to the turntable, a record transferring means operable to deliver the record disks from the supply onto the turntable and for returning them from the table to the supply, a reproducer, a supporting arm for the reproducer and a single means operable to simultaneously adjust the record supporting means and the said supporting arm relative to the turntable for the

accommodation of records of different diameter.

13. In a phonograph, a record-rotating means, means for sliding a record towards an operative position thereon, and co-operating record guiding means engaged by the record for guiding it during its sliding movement into operative position on the rotating means.

14. In a phonograph, a turntable, means for sliding a record towards said turntable, and movable record guiding means engaged by the outer periphery of said record, for guiding it into position on said turntable during its sliding movement.

15. In a phonograph, a turntable, means for sliding a record downwardly toward said turntable, and co-operating record guiding means for engaging the record and guiding it during its sliding movement into position on the turntable.

16. In a phonograph, a turntable, means for sliding a record downwardly towards said turntable, and co-operating record guiding means engaged by the outer periphery of the record for guiding it during its sliding movement into position on the turntable.

17. In a phonograph, a turntable, means inclining a record downwardly to slide towards said turntable, and a co-operating movable record guiding means engaged by the outer periphery of the record for guiding it during its sliding movement into position on the turntable.

18. In a phonograph, a turntable, means inclining a record downwardly to slide towards said turntable, and a co-operating pivotally mounted record guiding means engaging the outer periphery of the record and guiding it during its sliding movement into position on the turntable.

19. In a phonograph, a turntable, means inclining a record downwardly to slide towards said turntable, and a co-operating pivotally mounted record guiding means engaging the outer periphery of the record and guiding it during its sliding movement into position on the turntable, and means for moving said pivotally mounted guide means through a definite cycle.

20. In a phonograph, a turntable, means supporting a group of records adjacent to the turntable, means for removing a record from said group of records, means for sliding said removed record towards the turntable, and means for guiding the removed record into position on the turntable during its sliding movement.

21. The combination as in claim 20 said guide means operable to remove the record from the turntable.

22. The combination as in claim 20 said guide means being operable to remove said record from the turntable and return it to the group.

23. In a phonograph, a turntable, a record

magazine mounted adjacent the turntable for pivotal movement, means for removing a record from said magazine, means for moving said magazine about its pivot, and means carried by said magazine for engaging the removed record and moving it towards the turntable.

24. The combination as in claim 23 including guide means for receiving the record and guiding it into operative position on the turntable.

25. In a multiple playing phonograph, a rack for holding a group of records in abutting relation, means for removing a record from one end of said rack, and means for bodily moving the rack to advance the group of records therein to have a record move to occupy the space formerly occupied by the removed record.

26. In a multiple playing phonograph, a pivotally mounted rack for holding a group of records, means for removing a record from one side of said rack when the latter is in normal position, and means for swinging the rack on its pivot to advance the group of records therein to have a record move to occupy the space formerly occupied by the removed record.

27. In a phonograph, a turntable, a group of records to be played, means for sliding a record from the group toward said turntable, co-operating record guiding means engaged by the record for guiding it into operative position on the turntable, during its sliding movement, and means for operating said record guiding means to remove the record from the turntable after it has been played, and return it to the group.

28. In an automatic phonograph, a turntable, a fixed support at one side of said turntable, a magazine pivotally supported thereon adapted to hold a plurality of records, means for swinging said magazine about its pivotal support, and means for transferring a record from said magazine onto said turntable when said magazine is swung to one position and return a record from said turntable to said magazine when swung to another position.

29. In an automatic phonograph, a turntable, a magazine, means for pivotally supporting said magazine at one side of said turntable, and means for swinging said magazine to substantially a vertical position for receiving a record from said magazine and from the vertical position toward the horizontal position for discharging the record onto said turntable.

30. In an automatic phonograph, a turntable, a magazine positioned at one side of said turntable, means for pivotally supporting said magazine at one side of said turntable, means for swinging said magazine about said pivotal mounting, means for re-

turning a record from said turntable to said magazine when said magazine has swung to substantially a vertical position, and means for transferring a record from the magazine to the turntable as it swings to a substantially horizontal position.

31. In a machine of the character described, a turntable, a magazine for supporting a plurality of records adjacent said turntable, means for transferring records between said magazine and turntable, and means for adjusting the position of said magazine relative to the turntable for permitting records of different diameters to be transferred therebetween.

32. In a machine of the character described, a turntable, a magazine for supporting a plurality of record disks adjacent said turntable, mechanism for transferring a record from the magazine to the turntable and from the turntable to the magazine, and means for varying the distance between said magazine and turntable for permitting said mechanism to transfer records of different diameters therebetween.

33. In a machine of the character described, a turntable adapted to receive a record thereon, a reproducer including a tone arm, means for raising said reproducer and swinging it beyond the periphery of a record upon the completion thereof, swinging it inwardly and lowering it into engagement with said record for reproduction thereof, and a stop member associated therewith adapted to be engaged thereby when in its raised position for limiting its inward swinging movement to the proper position at the start of the record and disengaged thereby upon its being lowered into record engagement for permitting its continued inward movement over the record.

34. In a machine of the character described, a turntable adapted to receive a record thereon, a reproducer including a tone arm, means for raising said reproducer and swinging it beyond the periphery of a record upon the completion thereof, swinging it inwardly and lowering it into engagement with said record for reproduction thereof, a stop member associated therewith adapted to be engaged thereby when in its raised position for limiting its inward swinging movement to the proper position at the start of the record and disengaged thereby upon its being lowered into record engagement for permitting its continued inward movement over the record, and means on said stop member for rendering the same ineffective with respect to the outward swinging movement of said tone arm when in raised position.

35. In a phonograph, the combination with a turntable, and a reproducer including a tone arm, of means for positioning said reproducer at the beginning of a record, comprising means for elevating said reproducer

- above the level of the record on the turntable and lowering it into engagement therewith, means for swinging said reproducer outwardly beyond the periphery of said record and returning it toward the periphery thereof, and means for arresting the inward movement of the reproducer at the marginal edge of said record when in elevated position while releasing the same upon its being lowered into engagement with the record.
36. In a machine of the character described, a turntable, a supply of record disks adjacent thereto, an annular member pivotally mounted adjacent said turntable adapted to receive a record from said supply, means for causing said member to approach and concentrically encircle said turntable with said record engaged thereby to bring the peripheral edge of said record into engagement with the surface of the turntable, and means for rotating said turntable for imparting movement to the edge of said record to move it into position on said carrier for placement upon said turntable.
37. In an automatic phonograph, a turntable, a pivotally supported magazine adapted to hold a plurality of records, means for swinging said magazine about its pivotal mounting at one side of said turntable, and means for transferring a record from said magazine to said turntable when said magazine is swung to one position and returning said record to said magazine when it is swung to another position.
38. In an automatic phonograph, a turntable, a pivotally supported magazine adapted to hold a plurality of records, means for swinging said magazine about its pivotal mounting at one side of said turntable, and means for transferring a record from said magazine to the turntable when said magazine is swung to one position and lifting said record from said turntable for returning it to said magazine when it is swung to another position.

Signed at Seattle, Washington, this 30th day of March, 1928.

RALPH R. ERBE.
